ABSTRACT OF THE DISCLOSURE

Process for the manufacture of 4-hydroxybenzylphosphonic esters by reacting esters of phosphoric acid with 4-hydroxybenzylamines in the presence of a base. The compounds manufactured according to the invention are used as stabilizers.

The present invention relates to a process for the manufacture of compounds of the Formula I

wherein R₁ and R₂ denote a straight-chain or branched alkyl group, a cycloalkyl group or an aralkyl group, R₃ and R₄ independently of one another denote a straight-chain or branched alkyl group, a cycloalkyl group, an alkylthioalkyl group, an alkyloxalalkyl group, a halogenoalkyl group, an alkenyl group, the phenyl group or an alkylphenyl group, or together denote the groups

characterized in that 1 mol of a compound of the Formula II

wherein R₁ and R₂ have the abovementioned meaning and R₅ and R₆ independently of one another denote a straight-chain or branched alkyl group or together, and with inclusion of the nitrogen atom, denote a saturated heterocyclic ring, are reacted with one mol of a compound of the Formula III

wherein R₃ and R₄ have the abovementioned meaning, in the presence of a base.

It is known to manufacture p-hydroxybenzylphosphonates by reaction of appropriately substituted benzyl halides with trialkyl phosphites in the sense of an Arbusow reaction. In this, one alkyl group of the phosphite is split off as alkyl halide. The removal from the end product of the alkyl halide which has been split off frequently presents difficulties, especially where a higher alkyl halide, such as, for example, octadecyl chloride, is concerned.

In contrast, the process according to the invention avoids the formation of an alkyl halide during the reaction, which substantially facilitates the purification of the end product. Furthermore, the process according to the invention is economically advantageous since the dialkyl

2

phosphite of the Formula III which is employed is almost completely incorporated into the end product of the Formula I, whereas according to the previously known process a part of the trialkyl phosphite is lost in the form of the alkyl halide. The fact that the splitting off of an alkyl halide is avoided in the process according to the invention also signifies a technological advance inasmuch as alkyl halides, especially lower alkyl halides, have to be destroyed by combustion, where, because of the halogen content, expensive absorption installations are needed to avoid contaminating the atmosphere. Finally, the substituted benzyl halides required for the previously known manufacturing process are unstable compounds of poor stability on storage, whilst the starting products of the Formula II required for the process according to the invention are stable compounds which can be stored.

It is furthermore known to manufacture compounds of the Formula I by reaction of appropriately substituted benzyl alcohols with trialkyl phosphites or triaryl phosphites, whilst splitting off alcohols or phenols, respectively. The benzyl alcohols required for this are however industrially more difficult to obtain than the starting products of the Formula II required for the process according to the invention. In other respects, what has been stated above applies as regards the more advantageous use of dialkyl phosphites in accordance with the process of the invention.

Finally it is known to manufacture compounds of the Formula I by reaction of appropriately substituted benzyltrialkylammonium iodides with trialkyl phosphites in the sense of a modified Arbusow reaction. However, the manufacture of the benzyltrialkylammonium iodides requires a further process stage as compared to the starting products of the Formula II which can be used according to the invention. In other respects, this process suffers from the same disadvantages as the Arbusow reaction of benzyl halides with trialkyl phosphites, described above.

Further general advantages of the process according to the invention are the relatively low reaction temperatures and the short reaction times, which repress the undesired formation of colored by-products. The dialkylamines split off during the reaction can easily be removed because of their volatility and can furthermore be trapped and re-employed for the manufacture of the starting products of the Formula II, which represents a further advantage industrially. Furthermore, the dialkyl phosphites used in the process according to the invention are substantially less volatile than the corresponding trialkyl phosphites hitherto used and therefore produce a distinctly less objectionable odor during the reaction.

According to the invention, it is preferred to manufacture compounds of the Formula I in which R₁ and R₂ independently of one another denote a straight-chain or branched alkyl group with 1 to 8 carbon atoms or a cycloalkyl group with 6 to 8 carbon atoms and R₃ and R₄ independently of one another denote a straight-chain or branched alkyl group with 1-22 carbon atoms, a cycloalkyl group with 6-8 carbon atoms, the groups

wherein the alkyl groups possess 1-18 carbon atoms, the phenyl group or an alkylphenyl group with 7-14 carbon atoms.

In the preferred embodiment of the process according to the invention, compounds of the Formula II are used in which R₅ and R₆ independently of one another denote a straight-chain or branched alkyl group with 1 to 5 carbon atoms or together, with inclusion of the nitrogen

atom, form a hydrogenated heterocyclic 5-membered or 6-membered ring.

It is particularly preferred, according to the invention, to manufacture compounds of the Formula I in which R_1 denotes methyl or branched alkyl with 3-4 carbon atoms, R_2 denotes branched alkyl with 3 or 4 carbon atoms and R_3 and R_4 denote straight-chain or branched alkyl groups with 1-18 carbon atoms. Compounds of the Formula II in which R_5 and R_6 denote methyl, ethyl, propyl or isopropyl or together denote the radical of piperidine or morpholine are particularly preferentially employed for the manufacture of the compounds of the Formula I.

The process according to the invention can be carried out in the absence or in the presence of a solvent. Preferably, no solvent is used.

If R_1 , R_2 , R_3 , R_4 , R_5 and R_6 represent alkyl groups, these can, within the framework of the limits which have been indicated, be methyl, ethyl, propyl, isopropyl, butyl, isobutyl, tert.butyl, amyl, tert.amyl, hexyl, heptyl, octyl, nonyl, decyl, undecyl, dodecyl, tetradecyl, hexadecyl, octadecyl, eicosyl or docosyl. These groups may also be alkyl substituents if R_3 and R_4 denote alkylphenyl. If R_3 and R_4 are halogenoalkyl groups, then these are preferably chloroalkyl groups with 1-18 carbon atoms, such as, for example, 2-chloroethyl. R_1 and R_2 can also be cyclic alkyl groups with 6 to 8 carbon atoms. These can be, for example, cyclohexyl, cycloheptyl or cyclooctyl, and the preferred cyclic alkyl group is the 1-methylcyclohexyl-(1) group. If R_1 and R_2 are aralkyl groups, these can be groups with 7-12 carbon atoms, such as benzyl or phenylethyl. If R_5 and R_6 , with inclusion of the nitrogen atom, form a heterocyclic 5-membered or 6-membered ring, then this can be, for example, the radical of morpholine or piperidine.

If R_3 is alkylthioalkyl, it can be hexadecylthioethyl, dodecylthioethyl, hexylthioethyl, octadecylthiopropyl, dodecylthiopropyl or hexylthiopropyl. If R_3 denotes alkyl-oxalalkyl, this can be octadecyloxyethyl or dodecyloxyethyl. R_3 as alkenyl is, for example, allyl.

If solvents are used in the process according to the invention, then these can be aromatic hydrocarbons such as benzene or toluene, higher-boiling ethers, such as dioxane or ethylene glycol dimethyl ether, or aliphatic hydrocarbons or hydrocarbon mixtures, such as ligroin. Bases in the process according to the invention are, for example, alkali amides such as LiNH_2 or NaNH_2 , alkali hydrides, such as NaH or LiH , alkali hydroxides, such as LiOH , NaOH or KOH , alcoholates such as NaOCH_3 , NaOC_2H_5 or $\text{Mg}(\text{OC}_2\text{H}_5)_2$. Alkali amides and alkali alcoholates are preferred.

Alkali compounds of the phosphites of the Formula III can also be employed as bases. Their manufacture is effected, for example, by adding an alkali metal such as sodium to a phosphite of the Formula III.

Examples of compounds of the Formula III are dimethyl phosphite, diethyl phosphite, dibutyl phosphite, dihexyl phosphite, di-2-ethylhexyl phosphite, dioctyl phosphite, didodecyl phosphite, dihexadecyl phosphite, dioctadecyl phosphite, didocosyl phosphite, diphenyl phosphite or di-p-octylphenyl phosphite.

The starting compounds of the Formula II can be manufactured from the corresponding 2,6-dialkylphenol, formaldehyde and a secondary amine HNR_5R_6 , as described, for example, in Netherlands Pat. 6803498.

In the process according to the invention, the reactants of the Formulae II and III are advantageously employed in molar ratios. Optionally, one of the two reactants can be used in an excess of up to 20%. The base is employed in amounts of 1-30 mol percent, preferably 5-10 mol percent, relative to one of the reactants of the Formula II or III.

The temperature in the process according to the invention are not critical. They are only important with regard to the speed with which the reaction takes place. If, for example, the reaction is carried out at 100°C.,

the reaction time is between 60 minutes and a few hours. Preferred temperature ranges are 60-120°C.

The reaction according to the invention is preferably carried out under nitrogen or a noble gas, at normal pressure or reduced pressure, such as, for example, 10-100 mm. Hg. The reaction according to the invention can be carried out, for example, by warming the Compounds II and III and the base, without solvents, under reduced pressure until no further amine is evolved, or by adding the base to a solution of the Compound III and then adding the compound II, in the same solvent as the Compound III, at elevated temperature.

The compounds obtained in accordance with the process of the invention are outstandingly suitable for use as stabilizers against the thermo-oxidative and/or photo-induced degradation of monomeric and polymeric substances, especially for the stabilization of polypropylene, of polyethylene, of polyamides, of polyacetals or of copolymers of ethylene, propylene and a diene such as, for example, norbornadiene or dicyclopentadiene.

The invention is explained in more detail in the examples which follow:

EXAMPLE 1

13.8 g. (0.1 mol) of diethyl phosphite are initially introduced into 100 ml. of toluene and 0.69 g. (0.03 mol) of metallic sodium is added. The temperature rises to 40°C. whilst the sodium dissolves. The solution is treated with 26.3 g. (0.1 mol) of (4-hydroxy-3,5-di-tert.butylbenzyl)-dimethylamine in 150 ml. of toluene and the mixture is boiled for one hour under reflux, in the course of which gaseous dimethylamine is evolved. When the evolution of dimethylamine has ceased, the mixture is cooled, water is added and the toluene phase is washed until neutral and evaporated. The residue is recrystallized from ligroin. 26.8 g. (75%) of 4-hydroxy-3,5-di-tert.butylbenzyl-phosphonic acid diethyl ester of melting point 122°C. are thus obtained.

If in this example the diethyl phosphite is replaced by an equimolecular amount of a phosphorous acid diester of Table I below, and otherwise the same procedure is followed, the 4-hydroxy-3,5-di-tert.butylbenzyl-phosphonic acid diesters having the physical properties indicated are obtained in similar yields.

TABLE I

4-hydroxy-3,5-di-tert.butylbenzyl-phosphonic acid diester			
Boiling point			
Phosphorous acid diester	°C.	Mn.	Melting point
$(\text{CH}_3\text{O})_2\text{PHO}$	155-157°C.		
$(\text{C}_2\text{H}_5\text{O})_2\text{PHO}$	180-184	0.2	45-48°C.
$(\text{C}_2\text{H}_{11}\text{O})_2\text{PHO}$			Light yellow oil.
CH_3			Do.
$(\text{C}_8\text{H}_{17}-\text{C}(\text{CH}_3)-\text{CH}_2\text{O})_2\text{PHO}$			
CH_3			
$(\text{CH}=\text{CH}-\text{CH}_2\text{O})_2\text{PHO}$	160-165	0.1	
$(\text{C}_1\text{H}_2\text{CH}_2\text{O})\text{PHO}$			113-117°C.

EXAMPLE 2

13.8 g. (0.1 mol) of diethyl phosphite and 29.1 g. (0.1 mol) of (4-hydroxy-3,5-di-tert-butylbenzyl)-diethylamine are mixed and heated to 80° C. whilst passing a slight stream of nitrogen through the mixture. After adding 0.1 g. (0.0044 mol) of lithium amide the pressure is reduced to 15 mm. Hg by means of a water pump and the mixture is warmed to 100° C. The evolution of diethylamine can be recognized from the vigorous formation of bubbles. After one hour, 0.3 g. of glacial acetic acid and 50 ml. of ligroin are added. On cooling, 4-hydroxy-3,5-di-tert-butylbenzylphosphonic acid diethyl ester precipitates as a white crystalline substance. Melting point 122° C., yield 32 g. (90%).

If, in this example, (4-hydroxy-3,5-di-tert-butylbenzyl)-diethylamine is replaced by an equimolecular amount of (3-tert.butyl-4-hydroxy-5-methyl-benzyl)-diethylamine and the analogous procedure is followed, and various dialkyl phosphites are employed, the (3-tert.butyl-4-hydroxy-5-methylbenzyl)-phosphonic acid dialkyl esters indicated in Table II are obtained in good yield.

TABLE II

Dialkyl phosphite	3-tert.butyl-4-hydroxy-5-methylbenzyl-phosphonic acid dialkyl ester		Melting point, °C.
	Boiling point °C.	Mm. point, °C.	
(C ₂ H ₅ O) ₂ PHO	-----	102	
(C ₂ H ₅ O) ₂ PHO	-----	102	
(C ₄ H ₉ -CH ₂ -CH ₂ O) ₂ PHO	216	5	-----
C ₂ H ₅			
(C ₈ H ₁₇ O) ₂ PHO	-----	69-71	

EXAMPLE 3

29.3 g. (0.05 mol) of dioctadecyl phosphite and 13.3 (0.05 mol) of (4-hydroxy-3,5-di-tert-butylbenzyl)-dimethylamine are mixed and heated to 60° C. whilst passing a slight stream of nitrogen through the mixture, whereupon a homogeneous melt is produced. After adding 0.3 g. (0.013 mol) of lithium amide, the pressure is reduced to 15 mm. Hg by means of a water pump and the mixture is slowly warmed to 100° C., in the course of which the evolution of dimethylamine starts at 80° C. After one hour the mixture is cooled to 50° C. and 1.0 g. of glacial acetic acid is added. On cooling to room temperature, the melt solidifies. After recrystallization from acetone, 35 g. (90%) of 4-hydroxy-3,5-di-

65

tert.butylbenzyl-phosphonic acid dioctadecyl ester of melting point 57° C. are obtained.

If, in this example, the dioctadecyl phosphite is replaced by an equimolecular amount of a phosphorous acid diester from Table III and the analogous procedure is followed, the 4-hydroxy-3,5-di-tert.butylbenzyl-phosphonic acid diesters having the melting points indicated are obtained in yields of over 85%.

TABLE III

¹ Of the 4-hydroxy-3,5-di-tert.butylbenzyl-phosphonic acid diester.

EXAMPLE 4

23.4 g. (0.1 mol) of diphenyl phosphite are initially introduced into 50 ml. of absolute toluene, the solution is cooled to 5° C. and 0.48 g. (0.02 mol) of sodium hydride is added. The mixture is heated to the boil and a solution of 26.3 g. (0.1 mol) of (4-hydroxy-3,5-di-tert.butyl)-dimethylamine in 100 ml. of absolute toluene is added dropwise. Thereafter the mixture is further boiled until the evolution of dimethylamine ceases (approx. 4 hours). After cooling, the mixture is neutralized with a little glacial acetic acid, water is added and the toluene phase is washed until neutral and evaporated. The residue is recrystallized from hexane. 33 g. (73%) of 4-hydroxy-3,5-di-tert.butylbenzyl-phosphonic acid diphenyl ester of melting point 135° C. are thus obtained.

If, in this example, the diphenyl phosphite is replaced by an equimolecular amount of di-tert.octylphenyl phosphite and otherwise the same procedure is followed, 4-hydroxy-3,5-di-tert.butylbenzyl-phosphonic acid di-(tert.octylphenyl) ester is obtained in good yield, after distilling off the solvent, as a glass of a slight yellow color.

EXAMPLE 5

65

13.8 g. (0.1 mol) of diethyl phosphite and 17.9 g. (0.1 mol) of (4-hydroxy-3,5-dimethylbenzyl)-dimethylamine are mixed and heated to 100° C. 0.4 g. (0.01 mol) of sodium methylate is added at this temperature and the pressure is then reduced to 15 mm. Hg. When the reaction has subsided, which requires approx. 1 hour, the mixture is cooled and neutralized with glacial acetic acid. The melt is digested with hexane, whereupon crystallization occurs. After recrystallization from hexane, 4-hydroxy-3,5-dimethylbenzylphosphonic acid diethyl ester is obtained in a yield of 80%. Melting point: 72° C.

If, in this example, the (4-hydroxy-3,5-dimethylbenzyl)-dimethylamine is replaced by an equimolecular

amount of (4-hydroxy-3,5-diisopropylbenzyl)-dimethyl-amine and the analogous procedure is followed, 4-hydroxy-3,5-diisopropylbenzyl-phosphonic acid diethyl ester is obtained in a yield of 65%. The substance is liquid and has a boiling point of 163° C./0.15 mm. Hg.

EXAMPLE 6

13.8 g. (0.1 mol) of diethyl phosphite and 30.5 g. of 20 N-(4-hydroxy-3,5-di-tert-butylbenzyl)-morpholine (melting point 93–94° C.) are mixed and heated to 100° C. under nitrogen. After adding 0.2 g. (0.005 mol) of sodium amide, the pressure is reduced to 15 mm. Hg by means of a water pump and the mixture is kept at 100° C. for 2 hours. When the reaction has subsided, the mixture is cooled and neutralized with a little glacial acetic acid. On treating the reaction mixture with warm ligroin, 4-hydroxy-3,5-di-tert-butylbenzyl-phosphonic acid diethyl ester precipitates as crystals. Yield 28 g. (80%); melting point, after one recrystallization from ligroin: 122° C.

What is claimed is:

1. Process for the manufacture of compounds of the Formula I

wherein R₁ and R₂ denote a straight-chain or branched alkyl group, a cycloalkyl group or an aralkyl group, R₃ and R₄ independently of one another denote a straight-chain or branched alkyl group, a cycloalkyl group, an alkylthioalkyl group, an alkyloxalkyl group, a halogenoalkyl group, an alkenyl group, the phenyl group or an alkylphenyl group, or together denote the groups

which comprises reacting 1 mol of a compound of the Formula II

wherein R₁ and R₂ have the abovementioned meaning and R₅ and R₆ independently of one another denote a straight-chain or branched alkyl group or together, and with inclusion of the nitrogen atom, denote a saturated

heterocyclic ring, with one mol of a compound of the Formula III

wherein R₃ and R₄ have the abovementioned meaning, in the presence of a base selected from alkali amides, alkali hydrides, alkali hydroxides, alkali alcoholates, and alkali compounds of the phosphites of the Formula III.

2. Process according to claim 1, wherein in the Compound I, R₁ and R₂ denote a straight-chain or branched alkyl group or a cycloalkyl group and R₃ and R₄ independently of one another denote a straight-chain or branched alkyl group, a cycloalkyl group, an alkylthioalkyl group, an alkyloxalkyl group, an alkenyl group, the phenyl group or an alkylphenyl group or together denote the groups

3. Process according to claim 2, wherein lithium amide is used as the base.

4. Process according to claim 2, wherein the sodium compound of the compound of the Formula III is used as the base.

5. Process according to claim 2, wherein the reaction takes place in the presence of 1 to 30 mol percent of a base.

6. Process according to claim 2, wherein in the compound of the Formula I, R₁ and R₂ independently of one another denote a straight-chain or branched alkyl group with 1 to 8 carbon atoms or a cycloalkyl group with 6 to 8 carbon atoms and R₃ and R₄ independently of one another denote a straight-chain or branched alkyl group with 1–22 carbon atoms, a cycloalkyl group with 6–8 carbon atoms, the $-(\text{CH}_2)_{2-12}-\text{S}-$ alkyl or $-(\text{CH}_2)_{2-12}-\text{O}-$ alkyl groups, wherein the alkyl groups contain 1–18 carbon atoms, the phenyl group or an alkylphenyl group with 7–14 carbon atoms.

7. Process according to claim 2, wherein in the compound of the Formula II, R₅ and R₆ independently of one another denote alkyl with 1–5 carbon atoms or together and with inclusion of the nitrogen atom form a hydrogenated heterocyclic 5-membered or 6-membered ring.

8. Process according to claim 6, wherein in the Formula I, R₁ denotes methyl or branched alkyl with 3–4 carbon atoms, R₂ denotes branched alkyl with 3 or 4 carbon atoms and R₃ and R₄ denote straight-chain or branched alkyl groups with 1–18 carbon atoms.

9. Process according to claim 7, wherein in the Formula II, R₅ and R₆ denote methyl, ethyl, propyl or isopropyl or together denote the radical of piperidine or morpholine.

10. Process according to claim 7, wherein in the Formula II, R₅ and R₆ denote methyl, ethyl, propyl or isopropyl or together denote the radical of piperidine.
